UNITED STATES PATENT OFFICE

2,601,362

ADJUSTABLE MEMBER FOR HEAD
PROTECTIVE EQUIPMENTCharles Evans Bowers, Moylan, Pa., assignor to
The Fibre Metal Products Company, Chester,
Pa., a corporation of Pennsylvania

Application June 10, 1949, Serial No. 98,328

2 Claims. (Cl. 2—8)

1

The present invention deals with headgears such as are commonly employed as the supporting foundation for head protective equipment, and is concerned primarily with novel mechanism for adjusting an element of said headgear.

At the present time, it is common practice to employ a headgear as the supporting foundation for such head protective equipment as welding helmets, face shields, and other members designed to protect the head or face of a workman while engaged in dangerous activities. Such a headgear has now assumed a fairly well standardized conventional form. It consists essentially of a head encircling band and a top crosspiece which extends either from one side to the other of the headband or from one end to the other.

In order to insure of the accurate fit of such a headgear on the head of any particular workman so as to provide a good supporting foundation, there have been provided headbands which are adjustable in extent. Thus, they may be adjusted to accurately fit the head of any particular wearer.

The present invention has in view as its foremost objective, the provision of mechanism that is adapted to be included in the construction of an element of a headgear such as the headband or crosspiece and which mechanism is susceptible of quick and easy adjustment to vary the effective extent of the particular element in which it is included.

More in detail, the invention has as an object, the provision, in a headgear of the type indicated, of an element such as a crosspiece which comprises two flat strips of material arranged in alignment with the confronting ends relatively adjustable to vary the effective extent of the crosspiece. Secured to the end of one of these strips is a flattened-out casing which slidably receives the end of the other strip. The latter end is formed with a projection while the end which carries the casing has secured thereto a leaf spring formed with a plurality of openings, any one of which is adapted to receive said projection. The particular opening in which the spring is received determines the effective extent of the crosspiece.

Another object of the invention is to provide, in adjusting mechanism of the character indicated, a casing, the exposed wall of which is formed with a longitudinal slot arranged centrally thereof. This casing is anchored at one end to one of the crosspiece strips, and the other end of these strips enters the casing from the other

2

end. A leaf spring is anchored to the inner face of the casing wall formed with the slot at one end thereof, and the other end passes between this casing wall and the strip which enters therein. The leaf spring is adapted to be flexed, which action is permitted by the slot in the casing wall. When the spring is flexed, it is bowed outwardly and moved out of engagement with the projection. When the flexing force is removed and the spring straightened out, the bow is eliminated and the spring may be returned to its original condition, conforming to the shape of the casing in which the projection is received in one of the openings in the spring.

Another somewhat more detailed object of the invention is to provide, in adjusting mechanism of the type noted, a leaf spring which has a free end that is suitably shaped to facilitate its being flexed as it is engaged by the thumb of an operator.

Various other more detailed objects and advantages of the invention such as arise in connection with carrying out the above noted ideas in a practical embodiment will, in part become apparent, and in part be hereinafter stated as the description of the invention proceeds.

The invention therefore comprises novel adjusting mechanism that is incorporated in the crosspiece or headband of a headgear included as a part of head protective equipment. The adjusting mechanism consists essentially of a flattened-out casing curved to conform to the shape of a wearer's head and which is anchored at one end to the end of a strip making up the particular element in which the adjusting mechanism is included. The end of another strip also included as a part of the element, in which the mechanism is included, enters the casing at its other end. The outer exposed wall of the casing is formed with a central slot. A leaf spring has one end anchored to the inner face of this casing at one end of the slot and its other end passes between a wall of said casing and the strip at the other end. The latter strip is formed with a projection which is adapted to cooperate with any of a series of holes in said spring to complete a detachable connection between two strips and thereby determine the effective length of that element.

For a full and more complete understanding of the invention, reference may be had to the following description and accompanying drawing wherein:

Figure 1 is a perspective view of a face shield having a headgear that includes a crosspiece that

is rendered adjustable by the adjusting mechanism of this invention.

Figure 2 is a top plan view of the crosspiece shown in Figure 1.

Figure 3 is a longitudinal vertical section through the crosspiece and adjusting mechanism and is taken about on the plane represented by the line 3—3 of Figure 2; and

Figure 4 is a detailed top plan view of one strip and the leaf spring that is anchored thereto.

Referring now to the drawing wherein like reference characters denote corresponding parts, and first more particularly to Figure 1, a piece of protective equipment that is commonly known as a face shield is therein illustrated. In this connection, it is noted that the present invention is not to be confined to this particular type of protective equipment. It is susceptible of use with any head or face protective equipment which includes a headgear as a supporting foundation. As shown in Figure 1, the shield element 10 is anchored to a forehead covering part 11 that is pivotally mounted on a headgear that is referred to in its entirety by the reference character H. This headgear H comprises a headband 12 and a crosspiece 13.

The effective extent of the headband 12 is adjustable due to the fact that an elastic band 14 is included as a part thereof. The effective extent of the crosspiece 13 may be varied by the adjusting mechanism now to be described.

The crosspiece 13 is shown as consisting essentially of two strips 15 and 16 which may be made from an appropriate fibrous material that is adapted to be molded into a particular shape desired. These strips 15 and 16 have a curvature generally corresponding to that of a wearer's head as is clearly brought out in Figures 1 and 3. The strip 15 has an end designated 17 and the strip 16 an end designated 18. These strips 15 and 16 are arranged in alignment with the ends 17 and 18 in confronting spaced relation. The distance at which these ends are spaced apart determines the effective extent of the crosspiece 13.

A flattened-out casing is referred to in its entirety by the reference character C. This casing is also made from the fibrous material above identified. The casing C comprises an outer wall 19 and an inner wall 20 which are joined by curved side edges 21 and 22. The casing C also has a curvature corresponding to that of the wearer's head and which blends in with that of the strips 15 and 16.

The outer casing wall 19 is formed with an elongated slot 23 that is arranged substantially centrally thereof. It will be noted that the end 17 of the strip 15 is disposed within the casing C between the walls 19 and 20. A leaf spring designated 24 has one end positioned between the outer face of the strip 15 and the inner face of the outer casing wall 19. A rivet passes through aligned openings in the strip 15, spring 24, and outer casing wall 19 to securely anchor the casing C to the strip 15 and also to anchor one end of the spring 24 to this strip.

The spring 24 may be made from any appropriate metal having desired properties of flexibility. Bronze may be taken as one example of the metal from which this spring 24 is made. This spring 24 is formed with a series of openings 26 which preferably are spaced uniformly therealong.

The end 18 of the strip 16 is also disposed within the casing 18. This means that the strip

16 passes between the walls 19 and 20 at one end of the casing. The end of the leaf spring 24 remote from the anchorage 25 passes between the inner face of the outer wall 19 and the outer face of the strip 16. The free end of the spring 24 is provided with an appropriate operating member such as the turned back end shown at 27. It is evident that when this end is engaged by the thumb of the operator, pressure may be applied to the spring to cause an arching or bowing thereof, the latter action being permitted by the slot 23. The spring 24 has a width slightly less than that of the slot 23 so that it may move therethrough in the manner depicted in Figure 3.

Adjacent the end 18 of the strip 16, the latter is provided with a projection 28 that is adapted to enter and snugly interfit in any of the openings 26.

Operation

As above explained, the effective length of the crosspiece 13 is determined by the distance between the ends 17 and 18 of the strips 15 and 16. This distance in turn depends upon which of the openings 26 receives the pin 28.

When it is desired to make an adjustment, the operator places his hand about the strip 16 with the thumb bearing against the curled end 27 of the spring 24. An inner and endwise pressure is applied to the spring 24 and at the same time a force is applied to the strip 16 tending to move it inwardly. This action causes the spring 24 to be arched and bowed outwardly which releases that particular opening 26 which engaged the pin 28 from the latter. The strip 16 may now be freely moved within the casing C to bring the pin 28 into alignment with any opening 26 desired. The force which caused the bowing of the spring 24 is now relieved and the end 27 of the latter moved outwardly if necessary to flatten out this spring and move it downwardly so that the pin 28 will be received in the opening 26 with which it has been aligned thereby completing the adjustment.

It is evident that the foregoing adjustment may be quickly and easily carried out by any workman and once any particular adjustment is attained, there is no danger of the crosspiece being accidentally disturbed.

While the adjusting mechanism of this invention has been described as included in the crosspiece of a headgear, it is to be clearly understood that the invention is not to be limited in this respect. The adjusting mechanism is equally susceptible of being included in the headband of such a headgear or a crosspiece which extends from front to back.

While a preferred specific embodiment of the invention is hereinbefore set forth, it is to be clearly understood that the invention is not to be limited to the exact constructions, mechanisms, and devices illustrated and described because various modifications of these details may be provided in putting the invention into practice within the purview of the appended claims.

What is claimed is:

1. In a headgear for protective equipment, an element, the effective extent of which is to be varied and which element comprises two strips in alignment with their ends adjustably spaced apart, and mechanism for varying the distance between said spaced ends, said mechanism comprising a flattened-out casing having inner and outer walls curved to conform to the shape of a wearer's head, said outer wall being formed with

an elongated central slot, means for anchoring said casing to one of said strips with the end of the latter received in the casing, said casing slidably receiving the other of said strips, an outwardly extending projection on said last-mentioned strip adjacent to the end thereof, and a leaf spring having one end anchored to the strip to which said casing is secured and formed with a series of openings, any one of which is adapted to receive said projection, said spring being positioned in said slot through which it is adapted to move and having a free end positioned exteriorly of said casing with that portion of said spring adjacent said free end passing between the outer wall of said casing and the strip which is slidable therein.

2. In a headgear for protective equipment, an element, the effective extent of which is to be varied and which element comprises two strips in alignment with their ends adjustably spaced apart, and mechanism for varying the distance between said spaced ends, said mechanism comprising a flattened-out casing having inner and outer walls curved to conform to the shape of a wearer's head, said outer wall being formed with an elongated central slot, means for anchoring said casing to one of said strips with the end

of the latter received in the casing, said casing slidably receiving the other of said strips, an outwardly extending projection on said last-mentioned strip adjacent to the end thereof, a leaf spring having one end anchored to the strip to which said casing is secured and formed with a series of openings, any one of which is adapted to receive said projection, said spring being positioned in said slot through which it is adapted to move and having a free end positioned exteriorly of said casing with that portion of said spring adjacent said free end passing between the outer wall of said casing and the strip which is slidable therein, and a thumb engaging member on said free end of said leaf spring in the form of a turned-back end of said spring.
